John J. Mire
Attorney.

UNITED STATES PATENT OFFICE.

BERNHARD HAGEMANN, OF LANGENHORST, NEAR OCHTRUP, GERMANY.

LICKER-IN DEVICE FOR CARDING ENGINES.

Application filed April 29, 1925. Serial No. 26,779.

To all whom it may concern:

Be it known that I, BERNHARD HAGEMANN, a citizen of Germany, residing at Langenhorst, near Ochtrup, Province of Westfalen, 5 State of Prussia, Germany, have invented certain new and useful Improvements in Licker-In Devices for Carding Engines; and I do hereby declare the following to be a full, clear, and exact description of the invention, such as will enable others skilled in the art to which it appertains to make and use the same.

This invention relates to licker-in devices for carding engines of the kind used for preparing cotton fibres for spinning and it has for its object to provide a licker-in device by means of which all fibres useful for spinning are delivered to the main cylinder of the carding engine, with the waste so effectively separated by the licker-in that substantially all fibers are delivered to the carding machine.

This object is attained according to the invention by arranging ahead of the licker-in grate at least one knife and by constructing the said grate and more particularly the grate portion lying nearest the said knife in such a manner as to cause the draught of air set up by the licker-in cylinder to enter almost exclusively the space existing between the cylinder and the grate.

An embodiment of the subject-matter of the invention is illustrated in the accompanying drawing which shows a transverse section through the licker-in device and the neighbouring parts of the main cylinder of the carding engine arranged in succession thereto.

The licker-in device comprises, in a manner known per se, a cylinder A rotatable around a horizontal axis and provided on its shell surface with saw teeth a^1 . The cylinder A is adapted to be rotated by a mechanism, not shown, at a speed of about 400 40 revolutions per minute. B is a table designed to feed the cotton fleece C to be treated. This table has its head face b^1 arranged in close proximity to the saw teeth of the cylinder A and carries a roller D which, 45 when the device is working, delivers the cotton fleece C into the teeth a^1 of the cylinder A. The space between the face b^1 of the table B and the saw teeth a^1 is so small that the cotton grasped by the teeth a^1 of 50 the cylinder A in moving past the said head

face b^1 is combed. Arranged below the table is an interchangeable knife E which serves to break and crush impurities contained in the fibres. The knife E has the cross-section of an isosceles triangle and is arranged so that one of its equal sides, e^1 , is tangential or approximately tangential with relation to the cylinder A. The lower portion of the cylinder A is enveloped by a grate F the bars f^1 and f^2 of which extend parallelly to the axis of the cylinder A. The grate F comprises two portions of different construction, one portion mainly serving as a fibre catching grate and the other as a cleaning grate. The fibre catching grate 60 lies adjacent to the knife E and consists of a special catching bar f^3 and four bevelled grate bars f^4 which have a comparatively large distance from each other as well as from the teeth a^1 of the cylinder A. The 65 cleaning grate arranged in immediate succession to the catching grate includes a plurality of grate bars f^2 which have from each other and from the teeth a^1 of the cylinder A a considerably smaller distance than the 70 bars f^1 , so that this portion of the grate is 75 in effect a screen.

Mounted in succession to the described licker-in is the main cylinder G of a carding engine the card clothing g^1 of which takes 80 up for further treatment the cotton fibres cleaned by the licker-in.

The operation of the device is as follows: The licker-in cylinder A, the feeding roller D and the main cylinder G of the carding engine are rotated and the cotton fleece C lying on the feed table B is inserted beneath the roller D. The cotton fed by the roller D to the cylinder A is grasped by the saw teeth a^1 and combed at the head face b^1 of the table B. The combed fibres are then fed to the knife E which breaks and separates from the fibres the impurities contained therein. The draught of air set up by the rapidly rotating cylinder A is guided by the face e^1 of the knife E in such a manner that it flows into the space between the cylinder A and the fibre catching grate bars f^1 so that all cotton fibres carried along by the draught are securely fed to the fibre catching grate. The fibres flying onto the catching bar f^3 and the grate bars f^1 are carried on by the said draught of air which flows towards the cleaning grate f^2 , and after having been partly freed from impurities in 110

- passing over the fibre catching grate they enter the space between the cylinder and the cleaning grate bars f^2 where further impurities are separated from the fibres.
- 5 As soon as the cotton fibres have been carried beyond the cleaning grate they are taken up for further treatment by the card clothing g^1 of the main cylinder G of the carding engine.
- 10 The arrangement of at least one knife E which directs the draught of air set up by the licker-in cylinder A into the space between the cylinder and the grate, produces the advantage that losses of useful cotton fibres such as are unavoidable in the well-known licker-in devices, can no longer occur. Those fibres which after passing the knife E are not grasped by the saw teeth a^1 and therefore have a tendency to drop between
- 15 the knife E and the catching bar f^3 of the fibre catching grate, are likewise carried on by the draught of air to the fibre catching grate bars f^1 and further to the cleaning grate bars f^2 . Besides, the provision of a
- 20 somewhat enlarged space between the rods f^1 of the fibre catching grate and the licker-in cylinder A and the arrangement of a special catching bar f^3 at the front edge of the fibre catching grate considerably facilitate the introduction of the draught of air into the cleaning grate.
- 25 Having thus described my invention, what

I claim as new and desire to secure by Letters-Patent, is:—

1. A licker-in device for carding engines, comprising feeders, a rotary licker-in cylinder, and a separating member arranged beneath the cylinder and providing in part a grate and in part a screen, a knife arranged ahead of the separating member with that face next the cylinder approximately tangential to such cylinder, the grate portion of the separating member having a fiber catching bar adjacent the knife and being spaced farther from the cylinder than the screen portion of the separating member, the latter being substantially concentric with the cylinder.

2. A licker-in device for carding engines, comprising a feeder, a rotary licker-in cylinder, a separating member arranged below the cylinder, and a knife interposed between the feeder and entrant end of the separating member, said knife having a face arranged substantially tangential to the cylinder, the entrant end of the separating device being spaced farther from the cylinder than the knife face, whereby the air current set up by the cylinder is guided by the knife into the space between the separating member and cylinder.

In testimony whereof I have signed my name to this specification.

BERNHARD HAGEMANN.
